UNITED STATES PATENT OFFICE.

BERT B. SUSANKA, OF CHICAGO, ILLINOIS.

WATER-PURIFYING APPARATUS.

SPECIFICATION forming part of Letters Patent No. 787,803, dated April 18, 1905.

Application filed July 20, 1904. Serial No. 217,355.

To all whom it may concern:

Be it known that I, BERT B. SUSANKA, a citizen of the United States, residing at Chicago, in the county of Cook and State of Illinois, have invented a new and useful Improvement in Water-Purifying Apparatus, of which the following is a specification.

My invention relates to an improvement in that part of apparatus for purifying water for industrial purposes by softening it with chemicals which proportions the quantity of the chemical solution employed to the raw water to be treated.

My primary object is to provide a construction of rotary valve device to be actuated by the power of the flow to the apparatus of the raw water to be treated to supply to the water the proper proportion of the chemical solution for treating it.

To this end my invention consists in the valve device combined with water-softening apparatus to produce the aforesaid result; and it also consists in details of construction and combinations of parts, all as hereinafter described and claimed.

Referring to the accompanying drawings, Figure 1 is a broken view in elevation, partly sectional, in the nature of a diagram, showing water-softening apparatus equipped with my improvement; Fig. 2, a broken view showing the valve device in longitudinal section with the ports of the valve in one of their two operative positions; and Fig. 3, a similar view of the same, showing the valve-ports in their other operative position.

1 is the valve device, comprising as its preferred construction (represented in Figs. 2 and 3) a casing 2, containing a tapering bore forming the valve-chamber or valve-seat, and having three openings 3, 4, and 5 in line with each other longitudinally of the casing on one side and two openings 6 and 7 on the opposite side in staggered relation to the first-named openings, and a tapering plug 8 rotatably confined within the casing to fit the same accurately and provided with diagonal ports 9, 10, 11, and 12. Pipes 13, 14, and 15 terminate, respectively, in the openings 3, 4, and 5, and pipes 16 and 17 terminate, respectively, in the openings 6 and 7 of the casing.

With the valve 8 in the position represented in Fig. 2 the ports 9 and 11 are closed by the casing-wall, while the port 10 connects the pipes 14 and 16 and the port 12 connects the pipes 15 and 17, and a half-turn of the valve 55 in its seat to the position represented in Fig. 3 causes the port 9 to connect the pipes 13 and 16 and the port 11 to connect the pipes 14 and 17 and brings the ends of the ports 10 and 12 against the casing-wall to close them 60 while the pipe 15 is out of coincidence with a valve-port and is closed by the valve.

Fig. 1 shows a preferred manner of utilizing the valve device of the described construction coöperatively in two situations in 65 a water-purifying apparatus. At 18 is represented a precipitating-tank containing baffle-plates 19, to which the water to be purified in it is fed after being mixed with a suitable chemical solution, (say of lime or soda,) 70 with a supply of the mixture, which in the arrangement illustrated is obtained from two similar mixing-tanks 20 and 21. A valve device 1 is interposed between the precipitating-tank and the mixing-tanks, with its pipes 13 75 and 15 discharging downward into the tank 18 and its pipes 16 and 17 respectively communicating with the mixing-tanks 20 and 21, while the pipe 14 serves for conducting to the apparatus the flow from any suitable source 80 (not shown) of the raw water to be treated. On the stem end 22 of this rotary valve are secured a pinion 23 and a sprocket 24. A lever 25 is fulcrumed centrally at 26 between the mixing-tanks to adapt it to be rocked on 85 its fulcrum under the action of a weight 27, movable, as by rolling, between stops 28 28 on the lever near its opposite ends, and an arm 29 depends from the lever and terminates in a segmental rack 30, engaging the pinion 90 23. In the mixing-tanks 20 and 21, respectively, are the floats 31 and 32, each supported on an end of the lever 25 by a bent arm 33, straddling the edge of the tank, and pivotally connected at its inner end with the float and 95 similarly connected at its outer end with the lever. Above the plane of the mixing-tanks is supported a chemical-solution tank 34, having journaled upon it a rock-shaft 35, carrying stirrers 36 36, depending into the tank, 100

and a belt-pulley 37. Below the solution-tank is supported another valve device 1, with its pipes 13^x and 15^x, (corresponding with the pipes 13 and 15 of the lower valve,) communicating, respectively, with the mixing-tanks 20 and 21 and with its pipe 14^x, (corresponding with the pipe 14 of the lower valve,) communicating with the solution-tank. The pipes 16^x and 17^x, which correspond, respectively, with the pipes 16 and 17 of the lower valve device, are each equipped with a flap-valve 38 for the purpose hereinafter explained, and each has a flexible section, preferably of rubber hose, 39, interposed between rigid sections of a pipe, the upper sections of the pipes terminating in inwardly-opening check-valves 40 and being adjustably supported by clamps 41 on vertical rods 42, depending from the solution-tank. The upper valve device 1 carries on its stem end a sprocket 43, connected by a chain 44 with the sprocket 24, and the pulley 37 is connected by a belt 45 with a smaller belt-pulley 46 on the stem end of the valve of the upper valve device 1.

The operation is as follows: Assuming, for starting, that the parts of the lower valve device 1 are in the relative positions shown of the valve represented in Fig. 3 and that the parts of the upper valve device are in relative positions shown of the valve represented in Fig. 2, raw water flowing through the pipe 14, port 11, and pipe 17 enters the tank 21 and eventually lifts the float 32 therein, with the result of raising the adjacent end of the lever 25 and causing the weight 27 to move upon it and assist in depressing it toward its opposite end. At the same time chemical solution flows from the tank 34, through the pipe 14^x and the respective valve-port 10, into the pipe 16^x and flexible section 39 thereof, filling the same to its check-valve 40 and closing the latter by the pressure of liquid against it. Meantime turning the valve of the lower valve device 1 is proceeding with the movement of the lever 25 on its fulcrum by engagement of the rack 30 with the pinion 23, and the sprocket connection between the two valves simultaneously turns that in the upper valve device until they occupy positions in their casings relatively reversed from those described, wherein raw water from the pipe 14 flows through the port 10 and pipe 16 into the tank 20, and solution from the tank 34 discharges through the pipe 14^x, respective port 11 into the pipe 17^x and its flexible section 39, filling the same to its check-valve 40 and closing the latter by the pressure of liquid, and the contents of the tank 21 discharge into the precipitating-tank through the pipe 17, valve-port 12, and pipe 15. With these ports in the valve of the upper valve device in the positions represented in Fig. 3 the contents of the pipe 16^x above the dotted line at 47 discharge through the port 9 and pipe 13^x

into the tank 20 when the float therein is down, and in discharging opens the respective check-valve 40 to facilitate the flow and the respective flap-valve 38 to vent the pipe 16^x and prevent siphoning of that portion of its contents below the line 47, and with the ports in the upper valve device in the positions represented in Fig. 2 the contents of the pipe 17^x above the dotted line at 47 discharge through the port 12 and pipe 15^x into the tank 21 when the float therein is down, and in discharging opens the respective check-valve 40 to facilitate the flow and the respective flap-valve 38 to vent the pipe 17^x and prevent siphoning of that portion of its contents below the line 47.

As will be understood in starting with filling raw water into, say, the tank 21, as described, the first charge of water in that tank will discharge without the addition to it of any solution; but thereafter chemical solution will enter the tank 20 from the pipe 16^x each time the float 31 descends, and the solution will enter the tank 21 from the pipe 17^x each time the float 32 is down.

Though the upper and lower valve devices are alike in all particulars, the ports in the upper valve may be of smaller diameter than those in the lower one, because the quantity of the liquid which passes through the upper valve is less than the quantity of the liquid which passes through the lower valve.

The flexible construction of the pipes 16^x 17^x adapts them for regulating the proportion of the chemical solution to be fed to the mixing-tanks, since by raising the pipes, which are held in their adjusted positions by the clamps 41, the quantity to be discharged from them may be increased, and by lowering them the quantity to be discharged may be decreased, according to the particular requirement for the raw water to be treated and the quantity thereof admitted for each charge into a mixing-tank.

The number of the ports in the valve of the device 1 may be any that is desired, thus one or more, without departure from my invention. Thus the valve device may be used for the raw water alone or for the solution alone and some other suitable proportioning means may be substituted for the valve device in one position, and if only one diagonal port is provided in the valve to connect two diagonally opposite openings in the valve-casing obviously there can only be a passage of liquid in one direction through the valve in one of the two positions thereof to which it is rotated. However, the employment of the valve as shown and described is believed to be the best for the purpose, though that may be modified in the matter of details without departure from my invention.

What I claim as new, and desire to secure by Letters Patent, is—

1. In water-purifying apparatus of the char-

acter described, the combination with the precipitating-tank and a mixing-tank, of a valve device, a discharge-pipe leading from an opening in the valve device to the precipitating-
5 tank and a pipe connecting another opening in the valve device with the mixing-tank, and a supply-pipe for the water to be treated leading to another opening in the valve device, means for operating said valve, in the path of
10 the flow to the apparatus of the water to be treated, to be actuated thereby, a chemical-solution tank communicating with the said mixing-tank, and means for proportioning the supply of solution entering the mixing-tank
15 to that of the raw water to be treated entering therein.

2. In water-purifying apparatus of the character described, the combination with the precipitating-tank and a mixing-tank discharging
20 therein, of a supply-pipe for the water to be treated leading to said mixing-tank, a chemical-solution tank, a valve device, a pipe leading from the solution-tank to an opening in the valve device, a pipe leading from another
25 opening in the valve device to said mixing-tank and an adjustable vented flexible pipe leading from another opening in the valve device, means for operating said valve, and means for proportioning the supply to the
30 mixing-tank of raw water to be treated to that of solution entering said mixing-tank from the chemical-solution tank.

3. In water-purifying apparatus of the character described, the combination with the precipitating-tank, of a pair of mixing-tanks and a chemical-solution tank, lower and upper valve devices supported, respectively, adjacent to said precipitating-tank and said solution-tank, discharge-pipes leading from two
35 openings in the lower valve device to the precipitating-tank, a raw-water-supply pipe leading to a third opening in said lower valve device, pipes leading from said two openings to said mixing-tanks, a pipe leading from said
40 solution-tank to an opening in the upper valve device, pipes leading from two other openings in said lower valve device to the respective mixing-tanks, and vented pipes leading from the two said openings in the upper valve device,
45 a lever geared to the lower valve, floats in the mixing-tanks connected with said lever near its opposite ends, and a connection between the upper and lower valves for effecting operation of the one by that of the other, sub-
50 stantly as and for the purpose set forth.

4. In water-purifying apparatus of the character described, the combination with the precipitating-tank, of a pair of mixing-tanks and

a chemical-solution tank, lower and upper valve devices supported, respectively, adjacent to said precipitating-tank and said solution-tank, discharge-pipes leading from two openings in the lower valve device to the precipitating-tank, a raw-water-supply pipe leading to a third opening in said lower valve device, pipes leading from said two openings to said mixing-tanks, a pipe leading from said solution-tank to an opening in the upper valve device, pipes leading from two other openings in the upper valve device to the respective
60 mixing-tanks, and vented pipes leading from the two said openings in the upper valve device, a pinion on the lower valve, a lever fulcrumed between its ends and having an arm provided with a segmental rack engaging said pinion, a weight movably confined on said lever, floats in the mixing-tanks connected with said lever near its opposite ends, and a connection between the upper and lower valves for effecting operation of the one by that of the other, substantially as and for the purpose set forth.

5. In water-purifying apparatus of the character described, the combination with the precipitating-tank of a pair of mixing-tanks, and a chemical-solution tank carrying a rock-shaft with stirrers depending therefrom into the tank, lower and upper valve devices supported, respectively, adjacent to said precipitating-tank and said solution-tank, discharge-pipes leading from two openings in the lower valve device to the precipitating-tank, a raw-water-supply pipe leading to a third opening in the lower valve device, pipes leading from said two openings to said mixing-tanks, a pipe leading from said solution-tank to an opening in the upper valve device, pipes leading from two other openings in the upper valve device to the respective mixing-tanks, and adjustable vented flexible pipes leading from the two said openings in the upper valve device, a pinion on the lower valve-sprockets on both valves and a chain connecting the sprockets, a lever fulcrumed between its ends and having an arm provided with a segmental rack engaging said pinion, a weight movably confined on said lever, floats in the mixing-tanks connected with said lever near its opposite ends, and a belt-and-pulley connection between said upper valve and said stirrer-shaft, the whole being constructed and arranged to operate substantially as described.

BERT B. SUSANKA.
